UNITED STATES PATENT OFFICE.

WILLIAM O. LLEWELLYN, OF WILKES-BARRE, PENNSYLVANIA.

AUTOMATIC BLOCK AND DEADLATCH.

Application filed April 5, 1922. Serial No. 549,740.

To all whom it may concern:

Be it known that I, WILLIAM O. LLEWELLYN, a citizen of the United States, residing at Wilkes-Barre, in the county of Luzerne 5 and State of Pennsylvania, have invented certain new and useful Improvements in Automatic Blocks and Deadlatches; and I do hereby declare the following to be a full, clear, and exact description of the invention, 10 such as will enable others skilled in the art to which it appertains to make and use the same.

This invention relates to new and useful improvements in automatic safety blocks and 15 dead latches especially adapted for use on mine railroads where it is desirous to provide a safety device for preventing runaway cars where such cars in numbers are stacked awaiting their turn for entering the mine 20 shaft to be loaded, and has for its primary object the provision of a head block and a derailer so located with respect to each other that in case of a car getting by the head block, said car will shortly thereafter be de- 25 railed and prevented from doing serious damages.

Another object of this invention is the provision of an operating means for positioning the head block and derailer to permit the passing of cars when desired and 30 which when released will permit the head block and derailer to assume their operative positions.

Another object of this invention is the 35 provision of an automatic block and dead lock of the above stated character which will be simple, durable and efficient, and which may be manufactured and sold at a comparatively low cost.

With these and other objects in view, as 40 will become more apparent as the description proceeds, the invention consists in certain novel features of construction, combination and arrangement of parts as will 45 be hereinafter more fully described and claimed.

For a complete understanding of my invention, reference is to be had to the following description and accompanying drawings, 50 in which:

Figure 1 is a side elevation, illustrating an automatic safety block and dead lock arranged on an inclined track and preventing a car from running away.

Figure 2 is a top plan view, illustrating 55 the same,

Figure 3 is an enlarged detail view, illustrating the operating means,

Figure 4 is a transverse sectional view, 60 illustrating the device.

Referring in detail to the drawings, the numeral 1 indicates a mine railroad track and on which cars are adapted to be stacked to await their turn to enter the mine shaft for loading and it is now compulsory by law 65 to provide a safety device for preventing such cars, while stacked on an incline, from running away. To comply with the law and to prevent property damage, I have provided an automatic safety block and dead latch 70 2 comprising a head block 3 of elongated formation which is pivotally supported at one end as shown at 4, while its other end is cut away to form an extension or shoulder 5 adapted to overlie one of the rails 6 of the 75 track 1 for the purpose of engaging one of the wheels of a car to act as a chock for the same. A link 7 is connected to the block 3 adjacent its free end and to a pivotally mounted bell crank lever 8 which is in turn 80 connected to a pivotally mounted operating lever 9 so that said block may be swung on its pivot towards and from the rail 6 when desired.

Located adjacent to the head block and 85 in the other rail 6 of the track is a dead latch 10 comprising a rail section 11 provided with a cut out portion 12 and said rail section has its end laterally curved, as 90 shown at 13, to cause or direct the wheels of a car off of the rails 6. A closing latch 14 is pivotally mounted, as shown at 15, and when in one position is adapted to form a continuation or a closure to the rail section so that the wheels of a car may 95

pass over the derailer on said rail section without being thrown off of the track. A spring housing 16 is located adjacent the frog and has located therein a tension spring 18 that is secured to a rod 19 which is in 100 turn connected to the latch 14 for the purpose of positioning the same to open the rail section and permit the derailing of a car. A rod 20 is connected to the pivoted end of the head block and to the free end of 105 the latch for the purpose of moving the latch into a closed position simultaneously with the movement of the head block into a position away from the other rail of the track so that a car may pass without obstruction.

As soon as the lever 9 is released, the

spring 18 returns the frog into an open position, rendering the derailer operative and also positions the head block over the other rail of the track to be engaged by 5 the wheel of a car, consequently chocking the car and preventing the same from running down grade. If for some reason the car should get by the chock end 5 of the head block, the wheels of said car immediately thereafter will be thrown off of the track by the derailer and consequently obviating any chance of the car running away or obtaining such momentum that it would do serious damage when derailed.

15 While I have shown and described the preferred embodiment of my invention, it will be understood that minor changes in construction, combination and arrangement of parts may be made without departing 20 from the spirit and scope of the invention as claimed.

Having thus described my invention what I claim is:

1. In combination with a railroad track, 25 a head block adapted when in one position to form a chock, a derailer for said track and located adjacent to the block, and manually actuated means for positioning the derailer in a closed position and simultaneously positioning the block laterally of the track and adapted to return the derailer to an open position and the block into its first position when manually released.

2. A device of the character set forth 35 including a railroad track, a pivotally mounted head block adapted when in one position to overlie one of the rails of the track to act as a chock for a car wheel, a derailer for said track and located adjacent

the block, means normally holding the derailer in an open position and the block in said position, and means for closing the derailer and simultaneously moving the block laterally of the track.

3. In combination with a railroad track, 45 a pivotally mounted block adapted when in one position to overlie one of the rails of the track to form a chock, a derailer in said track adjacent to the block, means connecting the derailer to the block, tension means connected to the derailer for normally holding the same in an open position and to hold the block in said first position, and an operating medium connected to the block for positioning the same laterally of the track and to close the derailer.

4. In a combination with a railroad track, a pivotally mounted block having one end positioned over one of the rails of the track 60 when in one position, a derailer in the track and located adjacent to the block, a bar connecting the block and derailer, tension means connected to the derailer for normally holding the same in an open position 65 and to place the block end in said first position, a link connected to the block, a pivotally mounted bell crank lever connected to said link, and an operating medium connected to said bell crank lever 70 for closing the derailer and for positioning the block laterally of the rail of the track.

In testimony whereof I affix my signature in presence of two witnesses.

WILLIAM O. LLEWELLYN.

Witnesses:

WILLIAM J. NEIMAN,
W.M. J. EVANS.
